UNITED STATES PATENT OFFICE.

HARRY E. CAMPBELL, OF MILWAUKEE, WISCONSIN, ASSIGNOR TO UNION ELECTRIC MFG. CO., OF MILWAUKEE, WISCONSIN, A CORPORATION OF WISCONSIN.

ELECTRIC SWITCH.

1,335,936.

Specification of Letters Patent. Patented Apr. 6, 1920.

Application filed September 2, 1919. Serial No. 321,181.

To all whom it may concern:

Be it known that I, HARRY E. CAMPBELL, a citizen of the United States, and resident of Milwaukee, in the county of Milwaukee and State of Wisconsin, have invented new and useful Improvements in Electric Switches, of which the following is a description, reference being had to the accompanying drawings, which are a part of this specification.

My invention relates to improvements in electric switches and more particularly to stationary contacts for switches in which the movable coöperating contacts are arranged to make a sliding contact therewith.

One object of the present invention is to provide a contact which may be readily removed for repairs, but which may be as easily replaced.

Another object of the invention is to provide covered spring means for readily detachably retaining the contact finger in pivotal connection with its support and for yieldingly urging the contact finger to engagement with the sliding contact.

A further object of the invention is to provide a simple but substantial contact which will insure a good electrical connection with its coöperating movable contact, and which will prove very durable in service.

With the above and other objects in view which will appear as the description proceeds, my invention resides in the novel construction, combination and arrangement of parts substantially as hereinafter described, and more particularly defined by the appended claims, it being understood that such changes in the precise embodiment of the herein disclosed invention may be made as come within the scope of the claims.

In the accompanying drawing, I have illustrated one complete example of the physical embodiment of my invention, constructed according to the best mode I have so far devised for the practical application of the principles thereof, and in which:

Figure 1 is a side elevation of my improved switch.

Fig. 2 is a top plan view thereof, parts being broken away and in sections to more clearly illustrate detailed construction.

Fig. 3 is a transverse sectional view taken on the line 3—3 of Fig. 1.

Fig. 4 is a side elevation of the switch, the switch finger being shown in raised position with its trunnions disengaged from the support and the spring means for maintaining the switch finger in pivotal connection with its support being removed, and;

Fig. 5 is a side elevation of the cap contained spring means for maintaining the switch finger in pivotal connection with its support, said means being detached from the switch.

My invention is particularly applicable to drum controllers, and therefore I have shown the invention used in such a connection in the accompanying drawing. It should be understood however, that contacts embodying my invention may be used for various other types of switches. It being unnecessary to show a complete controller in order to disclose my invention, I have merely shown one of the drum segments, and its coöperating contact finger. I have shown a shaft 1 having a contact segment 2 and mounted thereon and arranged to engage a contact finger 3. The contact finger 3 comprises an elongated bar of suitable conducting material such as brass, and the active end 5 of the contact finger has secured to the under side thereof, or formed integrally therewith a suitable contact portion 6 preferably curved to facilitate the engagement thereof with the contact segment 2. Near its rear end the contact finger has its side walls notched or recessed as at 7 to form at its rear end a pair of laterally projecting trunnions 8.

In drum controllers, it is customary to provide an insulating base 9 for supporting the contact fingers. This base may be formed of wood or any other desired material. To this base I secure by any suitable means such as screw 10, a support 11 for the contact finger. The support 11 as illustrated is of right angular shape, and has provided at the lower end of its vertical portion a terminal portion 12 having binding posts 13 and 14 thereon for making the desired electric connection with the contact finger. The contact support or bearing

block 11 may be formed of any suitable material, but in practice I prefer to form the same of brass, and formed on the top of the vertically extending surface of the support 5 port and near the outer end thereof is a pair of spaced upwardly extending ears 15 notched or recessed as at 16 to provide an open bearing for the trunnions 8. This arrangement in effect forms a trunnion bearing for the contact finger.

For maintaining the trunnions 8 of the contact finger in the recesses 16, and yet permitting the desired movement of the contact finger, I have provided a tension device 17. This device comprises a cap member formed from a single sheet of material and provided with a thimble or cup-shaped cylindrical outer closed end 18, having its inner ends directed outwardly and then downwardly to provide spaced arms 19 provided near their ends with slotted recesses 20 for detachable engagement with the reduced or grooved ends 21 of a pin 22 fixed in support 11. The member 17 is retained in position by means of an extensible spiral spring 23 confined in the cap member and having one end impinging against the closed outer end 18' and its other end carrying a cup or nipple member 24 attached to engage in a recess 25 in the support 11 and in the laminated lead connection 26 to be later described. This tension device provides means for yieldingly urging the contact portion 6 to engagement with segment 2 and at the same time provides convenient means for readily permitting the disengagement of trunnions 8 from recesses 16. To accomplish this, member 17 is rocked to the position depicted by dotted lines in Fig. 1 to 40 disengage slot 20 from the ends 21 of pin 20 as will be obvious.

For limiting the movement of the contact finger under the influence of the spring 23, I have provided the support 11 with an extension or projection 27 arranged to be engaged by an adjustable screw 28 carried by the contact finger and adjustably held in the desired position by means of a resilient locking member 29, also secured to the contact finger. With this arrangement the retention of the contact finger in engagement with its supporting base is insured, and the movement of said finger under the influence of spring 23 may be limited as desired, while the resiliency of the spring will allow said finger to yield to the movable contact and yet firmly hold the same in engagement therewith.

The laminated lead 26 insures a positive electrical connection between finger 3 and support 11 and has one end riveted or otherwise secured to finger 3 as at 30, and has its other end detachably secured to the support 11 by means of a bolt and nut member 31. As best shown in Fig. 4, the lead 26

also serves to retain the finger 3 in raised position from the movable contact 2 when the tension device 17 is removed.

From the foregoing description it will be readily seen that I provide a practical switch 70 which will be efficient and durable for the purpose described.

What I claim as my invention is:

1. An electric switch comprising a support, a contact finger pivotally carried by the support, a housing connectible with said support and having its major portion disposed over said contact finger, and spring means contained within the portion of said housing disposed over said contact finger for normally urging the same to engagement with a contact.

2. In an electric switch, in combination, a support, a contact finger having at one end an open pivotal bearing on said support and having at its other end a contact, a cap member detachably engaging said support, and means contained in said cap member for yieldingly maintaining the contact finger in engagement with the support and permitting the movement of said contact.

3. In an electric switch, in combination, a support, a contact finger having at one end an open pivotal bearing on said support and having at its other end a contact, a cap member detachably engageable with said support, and an extensible spring contained in said cap member for yieldingly maintaining the contact finger in engagement with the support and permitting the movement of said contact.

4. In an electric switch, in combination, a support, a contact finger having at one end an open pivotal bearing on said support and having at its other end a contact, a cap member disposed over said contact member near said pivotal bearing, and means contained in said cap member to hold the same in engagement with the support and permit movement of said contact.

5. In an electric switch, in combination, a support, a contact finger having at one end an open pivotal bearing on said support and having at its other end a contact, a cap member disposed over said contact arm near said pivotal bearing and having a bifurcated portion forming arms, said arms being engaged with the support, and means contained in said cap member and bearing against the contact finger to hold the same in engagement with support and permit movement of said contact finger.

6. In an electric switch, in combination, a support, a contact finger having at one end an open pivotal bearing on said support and having at its other end a contact, a cap member disposed over said contact arm near said pivotal bearing and having a bifurcated portion forming arms, means readily detachable securing the arms of said cap to

the support, and means contained in said cap member and bearing against the contact finger to hold the same in engagement with the support and permit movement of said contact finger.

7. In an electric switch, in combination, a support, a contact finger having at one end an open pivotal bearing on said support and having at its other end a contact, a cap member disposed over said contact finger, arms formed on said cap member and extending below the sides of said contact finger and provided with recesses, projections formed on said support and engageable with the recesses of said arms, and means contained in said cap member for resiliently bearing against the contact finger to hold the same in engagement with the support and permit movement of said contact finger.
8. In an electric switch, in combination, a support, a contact finger having at one end an open pivotal bearing on said support and having at its other end a contact, a cap member disposed over said contact finger, arms formed on said cap member and extending below the sides of said contact finger and provided with recesses, projections formed

on said support and engageable with the recesses of said arms, means contained in said cap member for yieldingly bearing against the contact finger to retain the same in engagement with the support and to permit the movement of said contact finger, and means juxtaposed said cap member and engaging said support to limit the pivotal movement of said contact finger.

9. In an electric switch, in combination, a support, a pair of notched upstanding ears on said support, a contact finger, trunnions formed on said finger at one end thereof, a contact portion at the other end of said finger, said trunnions engaging the notched ears of said support, resilient means for readily detachably retaining the trunnions in said notched ears to pivotally secure the contact finger to the support, means for detachably limiting the movement of the contact finger by said resilient means, and a laminated lead having one end riveted to said contact finger and its other end detachably fixed to said support.

In testimony whereof, I affix my signature.

HARRY E. CAMPBELL.
